Henry F. Wussow, Jr., Inventor,
By *D. J. Moore* Atty.

UNITED STATES PATENT OFFICE.

HENRY F. WUSSOW, JR., OF BONDUEL, WISCONSIN.

RAIL-JOINT.

1,271,646.

Specification of Letters Patent.

Patented July 9, 1918.

Application filed April 29, 1918. Serial No. 231,325.

To all whom it may concern:

Be it known that I, HENRY F. WUSSOW, Jr., a citizen of the United States, residing at Bonduel, in the county of Shawano and 5 State of Wisconsin, have invented certain new and useful Improvements in Rail-Joints, of which the following is a specification.

My invention relates to improvements in 10 rail joints, and refers particularly to improvements upon the type of rail joint or track fastening disclosed in the patent granted to Benjamin Wolhaupter, on September 17, 1912, the main object of this invention being to overcome certain defects 15 found to exist in said construction, which may be stated to consist in insufficient support for the head of the rails and the lack of means for locking the nuts used in securing the sections on each side of the meeting 20 ends of the rails.

The main purpose of my invention is the provision of a rail joint or track fastening which will properly join the meeting ends 25 of the rails and provide a strong and substantial support for the rails and which will also provide efficient means for locking the nuts on the fastening bolts thus insuring an efficient, desirable and practical improvement 30 in this class of inventions.

With this object in view my invention consists of a rail joint embodying novel features of construction and combination of parts substantially as shown, described and 35 claimed herein.

Figure 1 is a transverse sectional view of a rail joint embodying my invention.

Fig. 2 is a top plan view of the invention.

Fig. 3 is a detail view of the nut locking 40 means, and

Fig. 4 is a detail view of a modification.

Referring by letter to the drawings in which similar letters of reference denote the same parts in all the views:

45 The letter A designates the tread or head of the rail, B the web and C the foot or base all of the usual and well known construction, and fitting upon one side of the rails is the fish plate D, having the upper 50 face E, resting under the head of the rail, the base portion G, formed with the flange

H, to receive the securing means J, and also formed with the foot inclosing portion K, while for strengthening the said plate the series of ribs or braces L, are formed on one 55 side.

This fish plate D, rests upon one side of the web of the rail while upon the other side is placed the plate M, formed with the head supporting flange N and the foot engaging flange N¹, which construction of said plate thus provides the channel O, to receive the cushion strip P, and fitting against the outer vertical face of said strip is the flat vertical plate Q, formed with the outer 60 flange R, to receive the fastenings S, and is also formed with the horizontal portion S¹, which forms a support for the other side of the foot of the rails.

From this construction it will be noted 70 that the rails are secured between the two fish plates, that the said plates form perfect supports for the foot and head of the rails and that the said plates are separate, which permits easy and quick application or removal of the plates and to secure the ends 75 of the rails and the two sections in proper relation thereto I employ the headed transverse bolts T, whose threaded ends U receive the nuts U¹, and said nuts are secured when 80 home by the nut receiving recesses V, on the nut locking bar V¹, having slots W, to receive the securing means W¹, to fasten said bar in place.

I claim:

85 In combination with the ends of the rails, the plate disposed on one side having a vertical wall engaging the foot and head of the rails, a foot receiving portion and integral braces, a plate on the opposite side of the 90 rails engaging the head and foot thereof and formed with a channel, a cushion strip fitting said channel, a plate having a foot supporting portion and a vertical portion resting against the face of said cushion strip, 95 bolts for securing the rails and plates in proper relation, and nuts on said bolts.

In testimony whereof I affix my signature.

HENRY F. WUSSOW, JR.

Witnesses:

HENRY F. WUSSOW, Sr.,

AMANDA WUSSOW.
